(57) CLAIM

The ornamental design for a cup dispenser, as shown and described.

DESCRIPTION

FIG. 1 shows a perspective view;

FIG. 2 shows a top view;

FIG. 3 shows a front view;

FIG. 4 shows a side view;

FIG. 5 shows a back view; and,

FIG. 6 shows a bottom view.

The broken-line disclosure of a cup in the views is for illustrative purposes only and forms no part of the claimed design.

1 Claim, 2 Drawing Sheets
